CLAIM

The ornamental design for a cap for compressed gas cylinder, as shown and described.

DESCRIPTION

FIG. 1 is a top, front, and right side perspective view of a cap for compressed gas cylinder showing our new design, the top, rear, and left side perspective view being identical to FIG. 1;

FIG. 2 is a top, front, and left side perspective view thereof, the top, rear and right side perspective view being identical to FIG. 2;

FIG. 3 is a bottom, front, and right side perspective view thereof, the bottom, rear, and left side perspective view being identical to FIG. 3;

FIG. 4 is a bottom, front, and left side perspective view thereof, the bottom, rear, and right side perspective view being identical to FIG. 4;

FIG. 5 is a top plan view thereof;

FIG. 6 is a bottom plan view thereof;

FIG. 7 is a left side elevation view thereof;

FIG. 8 is front elevation view thereof;

FIG. 9 is a right side elevation view thereof; and,

FIG. 10 a rear elevation view thereof.

The dash-dash broken lines represent portions of the cap for compressed gas cylinder that form no part of the claimed design. The short dash-long dash broken lines define boundaries of the claimed design and form no part of the claimed design.

In some other embodiments, one or more features shown within the area bounded by the short dash-long dash boundary lines may form part of the claimed design. In some other embodiments, the combination of all of the features shown in dash-dash broken lines, all of the features shown within the dot-dash broken lines, and all of the features shown in solid lines forms the claimed design. In some other embodiments, the combination of all of the features shown in solid lines and all of the features shown in short dash-long dash boundary lines forms the claimed design.

(Continued)

ments, the combination of the gas cylinder with the illustrated cap for compressed gas cylinder forms the claimed design.
